CLAIM

The ornamental design for a Hi-Fi rack, as shown and described.

DESCRIPTION

1. HiFi rack

1.1 : Perspective

1.2 : Perspective

1.3 : Perspective

1.4 : Perspective

1.5 : Perspective

1.6 : Perspective

1.7 : Perspective

The four knobs of the support bars of the article are adjustable and are shown in alternate configurations in reproductions 1.3-1.6.

The two support bars on top of the article are removable and are shown in an alternate configuration in reproductions 1.3-1.6.

The broken lines depict portions of the article that form no part of the claimed design.

1 Claim, 7 Drawing Sheets(56)
